US00D748210S

(12) **United States Design Patent**
Kristiansen et al.

(10) **Patent No.:** **US D748,210 S**
(45) **Date of Patent:** **** Jan. 26, 2016**

(54) **STATIONARY FITTING BIKE**

(71) Applicant: **Cycling Sports Group, Inc.**, Wilton, CT (US)

(72) Inventors: **Morten Kristiansen**, Norwalk, CT (US); **Daniel L. Connors**, Southbury, CT (US)

(73) Assignee: **Cycling Sports Group, Inc.**, Wilton, CT (US)

(**) Term: **14 Years**

(21) Appl. No.: **29/494,387**

(22) Filed: **Jun. 19, 2014**

(51) **LOC (10) Cl.** **21-02**

(52) **U.S. Cl.**

USPC **D21/667**

(58) **Field of Classification Search**

USPC D21/663, 667, 666, 697, 694, 665, 668, D21/664; 482/61, 57, 58, 127, 133, 51, 9, 482/60, 904, 8, 1, 900, 63, 908; 188/24.11; 74/502.4, 502.6, 551.1, 551.8; 248/444.1, 205.1; D8/303; D12/178, D12/411

(57) **CLAIM**

We claim the ornamental design for a stationary fitting bike, as shown and described.

DESCRIPTION

FIG. 1 is a perspective view of the stationary fitting bike design;

FIG. 2 is a front view of the stationary fitting bike of FIG. 1; FIG. 3 is a rear view of the stationary fitting bike of FIG. 1; FIG. 4 is a right side elevation view of the stationary fitting bike of FIG. 1;

FIG. 5 is a left side elevation view of the stationary fitting bike of FIG. 1;

FIG. 6 is a top view of the stationary fitting bike of FIG. 1; and,

FIG. 7 is a bottom view of the stationary fitting bike of FIG. 1.

1 Claim, 7 Drawing Sheets
